UNITED STATES PATENT OFFICE.

FRANK M. WOJCIECHOWSKI, OF NORTH ATTLEBORO, MASSACHUSETTS, ASSIGNOR TO MARATHON COMPANY, OF ATTLEBORO, MASSACHUSETTS.

VANITY CASE.

Application filed December 29, 1927. Serial No. 243,241.

This invention relates to vanity cases, and pertains more particularly to a powder container or compartment therefor: the primary object of the invention being to provide a case wherein one of the hinged members thereof is provided with a novel form of combined powder container and puff compartment.

A further object of the invention is to provide a case with a dished cover having an inwardly curled rim and a partition therein which forms not only a powder compartment in conjunction with the bottom of the container, but also the bottom of a puff compartment that underlies the inwardly curled rim so that ample space is afforded to receive a relatively large puff, and wherein the rim serves to hold the puff within its compartment.

20 In the drawings:—

Figure 1 is a plan view of the invention in open position of the parts, and

Figure 2 is a section on line 2—2 of Figure 1.

25 In proceeding in accordance with the present invention a case is employed having a body 1 and a hinged cover 2.

The cover may be of any desired form, while the body has a dished bottom 3 and an inwardly curled rim 4 which overlies the bottom and is engaged by the cover 2 in closed position of the latter.

A disk or partition 5 of less diameter than that of the bottom has a flanged marginal edge 6 which latter seats on the bottom 3 and is suitably secured thereto, for example by means of solder 7 and forms a powder container or compartment in conjunction with the bottom 3. The disk 5, it will be noted is secured at such distance from the bounding edge of the bottom so as to form a substantially flat bottom or spot for a powder puff, which latter is engaged beneath the rim 4 and held on the disk 5 thereby.

45 From the foregoing it will be seen that a simple and compact construction is provided and wherein the disk 5 functions not only as the top of the powder compartment, but also as the bottom of the puff compartment, the bottom 3 and its integral continuation or rim 4 providing not only the bottom of the

powder compartment, but also the upper portion of the puff compartment.

The disk 5 has a preferably circular opening 6' serving as a filling inlet and dispensing outlet for the powder compartment. A rotary dispensing control disk 7 is pivoted at 8 to the disk 5 and has an opening 9 corresponding to and adapted to register with opening 6' and further has a circular foraminated area 10 likewise adapted to register with opening 6' so as to enable dispensing of the powder in a sifting-like manner. A finger engaging projection 11 is provided on the disk 7 to enable convenient rotation thereof. The present invention not only provides a compact structure, but also affords a puff compartment which can house a puff of maximum size in proportion to that of the case.

Having thus described my invention what I claim as new and desire to secure by Letters Patents is:—

1. In a vanity case, a body having a dished bottom and an inwardly curled rim, a cover hinged to the body and engageable within the rim, a disk of less diameter than that of the body having a central opening and a flanged marginal edge which latter seats on and is secured to the dished bottom of the body to form a powder compartment in conjunction therewith, and which disk underlies said rim to form a puff holding compartment in conjunction with the rim, and a rotary control disk pivoted to the first named disk, and having an opening adapted to register with the opening of the first named disk and further having a foraminated area also adapted to register with the opening of the first named disk.

2. In a vanity case, a body having a dished bottom and an inwardly curled rim, a cover hinged to the body and engageable within the rim, a disk having an apertured part secured to the dished bottom to form a powdering compartment in conjunction therewith, said disk underlying the rim to form a puff holding compartment in conjunction therewith, and a rotary control disk pivoted to the first named disk and having an apertured part adapted to register with the apertured part of the first named disk.

3. In a vanity case, a body having a dished

bottom, a disk secured at its periphery to the body to the bottom and having an apertured part, and a rotary control member carried by the disk and having an apertured dispensing part adapted to register with said apertured part of the first named disk.

4. In a vanity case, a body having a dished bottom and an inwardly curled rim, a cover hinged to the body and engageable within the

rim, a disk having an apertured part secured to the dished bottom to form a powder compartment in conjunction therewith, said disk underlying the rim to form a puff holding compartment in conjunction therewith, and control means for the apertured part. 10

In testimony whereof I have hereunto signed my name to this specification.

FRANK M. WOJCIECHOWSKI. 15
